[57] CLAIM

The ornamental design for a display device for boots, as shown and described.

DESCRIPTION

FIG. 1 is a front perspective view of the design for a display device for boots; and

FIG. 2 is a view of the design for a display device for boots similar to that of FIG. 1 except that it shows the device carrying a plurality of boots, which boots do not form any part of the design.

Fig. 2

Fig. 1
